UNITED STATES PATENT OFFICE

LESLIE ERNEST BROUGHAM, OF PURLEY, ENGLAND, ASSIGNOR TO THE ACCOUNTING & TABULATING CORPORATION OF GREAT BRITAIN LIMITED, OF LONDON, ENGLAND

RECORD CARD CONTROLLED LISTING OR TABULATING OR LIKE STATISTICAL MACHINE

Application filed October 27, 1931, Serial No. 571,446, and in Great Britain November 7, 1930.

This invention relates to a record card controlled listing or tabulating or like statistical machine, and has for its main object to provide a method and means of operation whereby the capacity of such machines is increased and whereby an increased number of operations can be obtained from a record card.

A further object of the invention is in the provision of such means which will enable a standard machine to be readily converted to function with increased capacity with little alteration to existing parts. To this end the invention employs printing elements controlled by settable swinging controlling members, in such a manner that for each setting of the swinging member a printing element may have a plurality of settings so that differential interpretations of a setting may be obtained. Each column of sensing members in the analyser is associated with a plurality of printing elements, which are arranged to be selectively actuated at will from the single column.

In order that the method of controlling the selective mechanism of listing, tabulating or like machines may be fully understood, the application to a card comprising in each column twelve possible positions for perforation records, will now be described, it being understood that this is by way of example only, as the method of control can be applied in a similar manner to cards in which the columns are of a different capacity.

It is convenient to refer to the lines on such a card by letters of the alphabet, as the embodiment now to be described refers to its employment for printing numerals. Accordingly, the lettering on the lines on the column from top to bottom will be from A to L consecutively.

As is well known a statistical card is divided up into fields each comprising a plurality of columns, and the perforations in a field are employed to select printing elements associated with the field.

For convenience of illustration the application of the method of control according to the invention to a field of five columns will now be described.

The field is divided up into sections, each section being employed to cause a selective operation of printing elements particular to the section, that is to say that from the one field including the five columns as many groups of elements will be operated as there are sections in the field. For convenience of illustration the division of the field into two sections only will be described.

The field is divided into halves so that the sections are equal. In the top section would be the lines in the columns corresponding to the letters B, C, D, E, F which represent the numerals 0, 1, 2, 3, 4, and for each column there may be made a perforation in the line A, and if such special ancillary perforation is employed then in conjunction with the perforations in the lines B, C, D, E, F, these latter perforations will have a modified or differential meaning, namely the numerals 5, 6, 7, 8, 9 respectively.

This arrangement as explained may occur in the upper half of the field and the printing elements particular to the upper part of these columns may be, and preferably are, the elements 1, 3, 5, 7, 9 in the unit operated by the field. Each unit will comprise ten such elements, the intermediate elements 2, 4, 6, 8, 10 being particular to the columns in the other half of the field as now to be explained.

In the lower half of the field the lines corresponding to the letters H, I, J, K, L represent the numerals 0, 1, 2, 3, 4, and if there are perforations in the line G then such special perforations become ancillary to the others and operate to produce a modified or differential interpretation of the perforations in the lines H, I, J, K, L, namely to represent the numerals 5, 6, 7, 8, 9.

It will therefore be seen that in each column of the field records can be provided in each half to represent any of the values from 0 to 9.

It will therefore be observed that a method of controlling according to the invention increases the recording capacity of an ordinary statistical card in that the capacity of each field is multiplied according to the number of sections employed in the field, that is to say in the example just described where the

field is divided into halves, the capacity of this field is doubled.

In order that constructions of listing or tabulating machines according to the invention may be clearly understood, the application, by way of example only, to a tabulator with printing elements controlled by swinging members of the kind described in United States Patent specification Serial No. 1,274,528, will now be described with reference to the accompanying drawing wherein—

Fig. 1 is a perspective view (partly diagrammatic) showing in elevation the method of controlling a plurality of printing elements from a single normal column on the card;

Fig. 2 is a perspective view of a part of the pin box showing the method of offsetting the extension rods to the stops in the stop basket.

For dealing with cards wherein a field comprises five columns divided into two equal sections, as previously described, to each field a printing unit comprising ten type bearing members TS numbered respectively 1—10, of which only the members 1 and 2 are shown in Fig. 1, will be employed.

In the drawing only one field of five columns is shown on the record card RC, the lines of the columns being designated A to L respectively, and the top section or half of the field including the lines A to F, and the lower section or half including the lines G to L, all as previously described.

The lines numbered B, C, D, E, F, in the top half and the lines numbered H, I, J, K, L, in the lower half of the field normally represent the numerals 0, 1, 2, 3, 4 respectively, the sectionalized columns in each half each being adapted for setting, through extension rods ER, diagrammatically illustrated by dotted lines in Fig. 1, corresponding rows of stops S associated with type bearing members TS.

The lines A and G are for ancillary perforations to obtain a differential interpretation of perforations in the other lines of the associated section, and are arranged to actuate corresponding selective or ancillary stops supplementary to the different columns, whereby, when an ancillary perforation occurs in a sectionalized column on the card, the stops associated therewith then represent the numerals 5, 6, 7, 8, 9.

Accordingly each type bearing member TS is provided with two sets of type t, the top set being numbered 0, 1, 2, 3, 4, and the bottom set being numbered 5, 6, 7, 8, 9, the first set being operated when ancillary perforations are not present and the latter when they are.

As will be clearly seen with reference to Fig. 1, each normal column of the card is respectively divided into two sectionalized columns with five places for possible holes

representing numerals, and one place for an ancillary hole in each, each sectionalized column having a corresponding row of six stops including the ancillary stop, the numeral stops each having an indication as to what numerals they represent.

Thus, to each normal column, two type bearing members are provided, thereby doubling the capacity of the column.

Associated with and controlling each member TS is a spring controlled swinging member AS, and the tabulator may be provided with an analyser PB, see Fig. 2, including as many spring pressed sensing pins SP as there are possible perforations in the lines B, C, D, E, F, and in the lines H, I, J, K, L of the card RC; these sensing pins actuating, in manner described in United States Patent specification Serial No. 1,245,502, the extension rods ER for controlling the stops which regulate the movement of the controlling swinging members AS for the type bearing elements TS. Swinging of the members AS is also effected and controlled by the springs SS in a similar manner to that as described in the United States Patent Specification Serial No. 1,245,502 above referred to.

In order that the sensing pins SP corresponding to the lines B, C, D, E, F may operate the members TS numbered respectively 1, 3, 5, 7, 9 of the unit, and that the sensing pins SP corresponding to the perforations in the lines H, I, J, K, L may control the swinging members AS of the printing members TS numbered respectively 2, 4, 6, 8, 10, it is preferred to connect the sensing pins corresponding to the perforations in the lower half of the field in normal manner to the stops S corresponding to the members TS numbered 2, 4, 6, 8, 10, and to offset the extension rods ER actuated by the sensing pins corresponding to the upper half of the field to actuate the members TS numbered 1, 3, 5, 7, 9, as will be clearly seen from Fig. 2.

In Fig. 2, only two columns of stops are shown respectively corresponding to members TS numbered 1 and 2, and associated with a single normal column of sensing pins SP, the extension rods ER connected to the sensing pins in the lines H, I, J, K, L leading directly to the stops in column numbered 2, and the extension rods connected to the sensing pins on the lines B, C, D, E, F having offset portions OS for leading them to the stops in column numbered 1.

The means for modifying the movement of the members TS produced by actuating the stops S aforesaid so as to obtain the differential interpretation thereof, comprises selective or ancillary sensing pins SSP corresponding to the lines A and G on the card, the sensing pins SSP in the line A sensing perforations in the upper part of the field and the sensing pins SSP in the line G sens-

ing perforations in the lower half of the field, these pins SSP being connected by extension rods ER to the supplementary ancillary stops SSS in the associated columns.

5 In a similar manner as the other sensing pins in the columns associated therewith, the extension rods ER for the sensing pins SSP in the line A are offset, and those corresponding to line G are connected direct, as will 10 be clearly seen from Fig. 2.

Each pair of members AS and TS are normally connected together by means of a latch LL, the construction being similar to that described in United States Patent specification Serial No. 1,274,528 and release of the latch permitting the member TS to swing forwardly under the action of the spring SS until the abutment AA engages the end of the slot SL when the second set of type t 20 will be in a position for operation upon the member AS being actuated.

The latches LL are actuated by actuators AM formed integral with the supplementary stops SSS, the latter extending up through 25 the stop basket, as explained in the United States Patent specification Serial No. 1,274,528 above referred to, so that when a supplementary stop is raised the actuator AM lifts the associated latch LL to free the members TS, and thereby permit of the second set of type t thereon being positioned. In Fig. 1 the type bearing member numbered 2 is shown with its second set of type t in 30 position, and with the heel of the member AS abutting the second stop in the associated column, so that the type numbered 6 is set adjacent the printing line on the platen P.

Restoration of the members AS and TS 40 subsequent to actuation may be effected in any well known manner, such as described in either of the British Patents hereinbefore referred to, the latches LL being held engaging the abutment AA under the action of the 45 spring LS each having one end connected to the associated member TS and the other end to a pivoted catch CH engaging the latch LL.

Thus, for any one column in the field there 50 are two sets of sensing pins SP and a stop pin SSP ancillary to the sensing pins, which modifies the movement of the corresponding printing element derived from the operation of the said sensing pins SP.

By such an arrangement it is possible to 55 print from each column in the field two numbers each of which can be any of the numerals between 0 and 9.

Accordingly, it will be seen that by constructions according to the present invention, a plurality of printing elements can be 60 actuated from a single column and consequentially the usefulness of the column is multiplied and the capacity of the machine consequentially increased.

65 Alternatively, stops and actuating means

for the latch as described in United States Patent specification Serial No. 1,274,528 may be actuated electrically as will be well understood in the art.

It will be seen that by a preferred construction according to the present invention a standard tabulator may be readily adapted to function with increased capacity as one wherein a plurality of printing sectors or elements are actuated from a single column of a card, although it will be understood that such a machine will be made ab initio.

What I claim is:

1. The combination with an analyser of a listing, tabulating or like statistical machine, having a plurality of type bearing members each associated with a settable controlling swinging member, of groups of settable stops for determining the movement of the swinging members at each operation of the machine, said groups of stops each corresponding to a predetermined section of a card column, ancillary stops to said groups for controlling the position of the type bearing members with respect to the swinging controlling members, special sensing members in the analyser for actuating said ancillary stops and means for actuating stops in a plurality of groups from a single column of sensing members corresponding to a card column in the analyser.

2. A listing, tabulating or like statistical machine, comprising in combination a plurality of type bearing members, a plurality of settable controlling swinging members each associated with and controlling the setting of a type bearing member; an analyser, means for setting a plurality of swinging members from a single column in the analyser, and means for obtaining differential settings of the type bearing members for each setting of the associated controlling swinging members.

3. A listing, tabulating or like statistical machine, comprising in combination with an analyser and a plurality of combined type bearing elements and swinging controlling elements therefor, greater than the number of columns of sensing members in the analyser, of means for actuating at will the surplus elements from the sensing columns selectively, and means for differentially controlling the setting of any type bearing element with respect to its associated swinging controlling element for each sensing position in the associated column.

4. A listing, tabulating or like statistical machine, comprising the combination with printing mechanism including type bearing elements respectively controlled by settable swinging controlling elements of analysing mechanism in which each column of sensing members is sectionalized, means for setting a predetermined swinging controlling member from each section and ancillary sensing means

to each section for differentially controlling the position of the respective type bearing elements with respect to the associated swinging controlling elements to obtain differential interpretation of each sensing position in a section.

5. In a listing, tabulating or like statistical machine, the combination with printing mechanism including type bearing elements respectively controlled by settable swinging controlling elements of a stop basket, including a row of stops for each swinging element, a pin box analyser of which each column comprises sensing pins less in number than the rows of stops, a connection box including normal and offset wiring between the rows of stops and the columns of sensing pins whereby a plurality of type bearing elements may be operated from a single column in the analyser and means for differentially controlling the position of the type bearing elements with respect to the associated swinging controlling elements to obtain differential interpretations of each sensing position.
6. In a listing, tabulating or like statistical machine the combination with printing mechanism including type bearing elements respectively controlled by settable swinging controlling elements of a stop basket, including a row of stops for each swinging member, a pin box analyser, of which each column of sensing pins is sectionalized, the number of sections corresponding to the number of rows of stops, a connection box including normal and offset wiring, the normal wiring proceeding between one section of a column and a row of stops, and the offset wiring between another section of said column and a row of stops, whereby a plurality of type bearing elements may be operated from a single column in the analyser, and ancillary sensing means to each section for differentially controlling the position of the respective type bearing elements with respect to the associated swinging controlling elements to obtain differential interpretation of each sensing position.

In testimony whereof I affix my signature.
LESLIE ERNEST BROUGHAM.
